UNITED STATES PATENT OFFICE.

FRANK L. CAPPS, OF BROOKLYN, NEW YORK, ASSIGNOR TO PATHE FRERES PHONOGRAPH COMPANY, OF NEW YORK, N. Y., A CORPORATION OF DELAWARE.

ADJUSTABLE SOUND-BOX.

1,324,643.

Specification of Letters Patent.

Patented Dec. 9, 1919.

Application filed January 5, 1917. Serial No. 140,669.

To all whom it may concern:

Be it known that I, FRANK L. CAPPS, a citizen of the United States, and a resident of Brooklyn, county of Kings, and State of New York, have invented certain new and useful Improvements in Adjustable Sound-Boxes, of which the following is a specification.

My invention relates to adjustable sound boxes and more particularly to the provision of a mounting therefor whereby the sound box may be brought into different positions for reproducing different kinds of records, as, for example, it may be used in one position with records having vertical cut grooves and in a different position with records having laterally undulating grooves.

An object of the present invention is to provide such an adjustable sound box which may be adjusted to different positions without substantially changing the position of the stylus or needle upon the record and without substantially affecting the relation between the sound conveying tube, commonly known as the tone arm, and such stylus or needle. One mode of obtaining this result may consist in mounting the reproducer so that it may be adjustably rotated to swivel upon an axis making an oblique angle with the reproducer diaphragm, and arranging the reproducer stylus or needle holder on the opposite side of the diaphragm, with the axis of its stylus socket or bore making an oblique angle therewith, and said bore and the stylus or needle held therein extending in the same general direction as a prolongation of the axis of the swivel mounting.

Another object of the invention is the provision of novel means for holding the sound box in its adjusted positions.

Other objects of the invention consist in the improvement of apparatus of the character described in various particulars, and with the foregoing and related objects in view, my invention consists in the parts, improvements and combinations herein set forth and claimed.

In the accompanying drawing I have illustrated one embodiment of my invention for the purpose of making the invention clearly understood, but I am not to be limited to the specific embodiment shown except as required by my claims, by which my invention is defined.

In said drawing, forming a part of this specification and wherein the same reference numerals are applied to designate the same parts throughout, Figure 1 is a side view of a sound box and connecting means for attaching it to a sound conveying tube such as a tone arm, said sound box being shown in this figure in the position adapted for the reproduction of records having vertical cut grooves and being equipped with a stylus adapted for such record. Fig. 2 is a front view of the sound box shown in Fig. 1. Fig. 3 is a view similar to Fig. 1, except that the sound box is turned in position for reproducing records having lateral cut grooves and equipped with a needle for such reproduction. Fig. 4 is a view taken substantially at right angles to Fig. 3, and Fig. 5 is a cross-sectional view taken on the line 5—5, Fig. 1.

The reproducer may be of any preferred construction. In the form shown it embodies a head 10 and a diaphragm 11 secured therein in any preferred manner, and an arm 12 connected to the diaphragm 11 and held by springs 13 to vibrate on knife edges 14 and comprising a stylus or needle holder 15 with means for securing the stylus or needle in place, as a thumb-screw 16. A socket or bore 17 is provided for receiving the shank of the stylus or needle. Such bore 17 preferably makes an oblique angle with the plane of diaphragm 11. In Figs. 1 and 2 a reproducing stylus 18 adapted for vertical cut records is shown, whereas in Figs. 3 and 4 a needle 18' adapted for records having lateral cut grooves is illustrated.

The reproducer neck 19 has substantially the form of an elbow and is preferably detachably secured to the reproducer head 10 as by screws 20 passing through a flange 21 provided on the neck 19, the arrangements of the parts being such that the axis of the bore of the neck 19 at the open end thereof farthest from the reproducer head 10 makes an oblique angle with the plane of diaphragm 11. The stylus 18, on the opposite side of diaphragm 11 likewise makes an oblique angle with the plane of said diaphragm and extends in the same general direction as the axis of neck 19, is received in a second elbow member 23 so as to turn therein, and provide a swiveling joint or coupling substantially closely adjacent to 110

the sound box or reproducer body. Preferably the elbow 19 is threaded on its exterior and the elbow 23 threaded on its interior so as to permit the parts to be screw-threaded together, but such screw-threaded connection is preferably not so tight as to cause the parts to bind, so that the elbows may be turned one within the other. While the part 19 is shown threaded within the part 23, it will be obvious that this relation, which is preferable on the score of appearance, may be reversed if desired, or the screw threads may be dispensed with, and other forms of swivel connection may be resorted to. Means are provided for holding the parts 19 and 23 relative to one another in adjusted positions. In the form shown the elbow 23 is provided within its screw-threaded portion with a hole 24 in which is received a ball 25, and such ball is urged inwardly by a spring 26 secured as by a screw 27 to the elbow 23, and sockets are provided in the elbow 19, and preferably in the screw-threaded part thereof, for receiving said ball 25 and holding the parts in adjusted position. In Fig. 5 the ball 25 is shown as seated in one of such recesses or sockets 28, and the second such recess or socket 29 is shown at practically 90° therefrom, though the precise location and distance apart of such seats may be varied from what is illustrated. The elbow 23 is provided with a neck 22 which may be inserted into or placed over the mouth of a suitable sound ejection tube, as, for example, the customary tone arm, a short section of which is shown at 22', and it will be understood that provisions are made, as is customary, for mounting such tone arm (or the entire horn of which the tone arm may form a part) so that the same may be rotated with the sound box on the end thereof and may also be moved substantially up and down so that the sound box may float upon the record and accommodate itself to any inequalities in the record, or in the record support, as the turn-table, or its bearings.

It is to be understood that while with such mounting as is illustrated my adjustable sound box is more particularly adapted for use on disk records, it may also be used on records of other forms, as, for example, cylindrical records.

When the reproducer is to be used on vertical cut records the parts are arranged in substantially the relative positions shown in Figs. 1 and 2, in which the diaphragm 11 is placed substantially at right angles to the groove being tracked, and is held in such position by the engagement of the ball 25 with a socket in the member 19. In such position the parts are supported, during sound reproduction, by the stylus 18 so that the reproducer and sound conveying tube or tone arm 22' attached to the neck 22 are sup-

ported from a tracking point substantially beneath the axis of the neck 22 extended, and the parts are in the position most conducive to proper floating action of the reproducer and its mounting upon the record surface.

For the reproduction of lateral cut grooves the parts are rotated to the position shown in Figs. 3 and 4, in which position they are held by the ball 25 seated in the socket provided for that purpose. In such position the diaphragm 11 is substantially parallel to the groove being tracked, and the needle 18, being vibrated laterally by the lateral cut groove, is adapted to impart vibration effectively to said diaphragm. It will be observed that in this position the relation of the tracking point T' to the neck 22, and the sound tube or tone arm to which the reproducer is attached by said neck 22, is substantially the same as in the position shown in Figs. 1 and 2, because of the axis of adjustment passing substantially through the tracking point T, and that the same efficient floating action is obtained as before the rotation of the reproducer to such adjusted position. In other words, the neck 22 and the sound tube or tone arm to which the reproducer is attached by the neck 22 are pointed in the same direction whether the reproducer be turned to the position shown in Figs. 1 and 2 or to that shown in Figs. 3 and 4, the tracking point in either case being substantially under the axis of the neck 22 and tone arm 22'.

It will be observed that with apparatus constructed as shown the assembly may be effected by first screwing the elbow neck 19 into its place within the elbow 23 and thereafter attaching the reproducer head as by means of the screws 20. When the parts have been assembled in this way there is no danger of their being screwed apart to a farther distance than is proper, since should any attempt be made to screw them apart, the head 10 will come in contact with the elbow 23 and prevent rotation thereof except through a part of one turn, further rotation being prevented by contact of the head 10 with the elbow 23.

A construction such as illustrated can be very readily and inexpensively manufactured, a smooth, continuous passage for the sound waves is provided without excessive bends or turns, and the parts may be readily adjusted for playing different types of records with no greater necessity for removal or replacement of parts than the provision of the form of needle or stylus adapted for the particular record desired to be played.

It is to be understood that while the embodiment illustrated is preferred, the same is for the purpose of affording a clear understanding of my invention only, and numerous changes therein and departures there-

from may be resorted to within the scope of my claims and without departing from my invention or sacrificing any of its advantages.

5 Having thus described my invention, I claim:

1. The combination of a sound box, a short neck having the form of an elbow projecting substantially centrally out of the back thereof and having its open end extending at an acute angle to the plane of the sound box diaphragm, a second elbow member in which the first-named elbow is rotatably mounted, the two elbows forming a sound 10 eduction tube, and the sound box being provided on the opposite side of the diaphragm therefrom with a holder adapted to hold a reproducer point with the axis thereof extending in the same general direction as the 15 axis of rotation of the first-named elbow upon the second-named elbow.

2. The combination of a sound-box, a hollow neck projecting out of the back thereof and having its open end at an acute angle 20 to the plane of the sound box diaphragm, a second elbow in which the first is rotatably mounted, such rotatable mounting being closely adjacent to the sound box body, and an arm on said reproducer comprising a reproducer point holder adapted to hold a 25 reproducing point with the axis thereof extending in the same general direction as the axis of the open end of the reproducer neck.

3. The combination of a sound box, an 30 elbow neck detachably secured to the rear thereof, and a second elbow in which the first elbow is screw-threaded, the sound box being in position to prevent the rotation of one elbow with respect to the other except 35 through a limited range without detaching the sound box from the elbow neck.

4. The combination of a tone-arm and a sound box having a diaphragm, said tone-arm and sound box being provided with a 40 swiveling connection, the plane of the diaphragm being inclined with respect to the axis of swiveling, a stylus arm adapted to impart vibration to the diaphragm, and means on said arm for holding a needle or 45 stylus at an oblique angle to the plane of the diaphragm and with its tracking point extending in the same general direction as the swiveling axis.

5. The combination of a tone-arm, a sound 50 box swiveled to turn thereon into two reproducing positions, said sound box being provided with a diaphragm arranged at an

oblique angle to the swivel axis and with a stylus arm for imparting vibration to the diaphragm, and means on said arm for holding a reproducing needle or stylus at an angle to the diaphragm and substantially parallel to the swivel axis.

6. The combination of a tone arm with the open end thereof directed downwardly 55 and having an axis at an oblique angle to the longitudinal axis of the tone arm, a sound box having a swiveling connection therewith, the swiveling axis coinciding with the axis of said open end, a diaphragm in said sound 60 box, and arranged with the plane thereof making an oblique angle to said swiveling axis, the longitudinal axis of the tone arm extended passing through said diaphragm, and a reproducing point holder adapted to 70 hold a reproducing point at an oblique angle to the plane of said diaphragm, and means for connecting said holder to the diaphragm.

7. A tone arm, a sound box having a swiveling connection therewith with the swiveling axis at an oblique angle to the longitudinal axis of the tone arm, a diaphragm in said sound box located opposite the end of the tone arm and extending substantially crosswise 80 of the axis of the tone arm, and means for holding a stylus or needle at an oblique angle to the diaphragm carried by the sound box and having an operative connection with said diaphragm.

8. A tone arm, a sound box having a swiveling connection with the tone arm and at an oblique angle to the longitudinal axis thereof, a diaphragm in said sound box at an oblique angle to the swiveling axis and a holder adapted to hold a stylus member at 95 an angle oblique to the plane of said diaphragm, and means for operatively connecting said holder to said diaphragm.

9. The combination of a phonograph tone arm, and a reproducer mounted for rotation 100 thereon, said reproducer comprising a diaphragm arranged at an oblique angle to the axis of rotation, means for holding a reproducer stylus member at an oblique angle to said diaphragm, the tracking point of the 105 reproducer stylus member being substantially directly beneath the axis of the tone arm extended in all positions of the reproducer.

In testimony that I claim the foregoing, I 110 hereto set my hand, this 29th day of December, 1916.

FRANK L. CAPPS.
